UNITED STATES PATENT OFFICE

95,403

DESIGN FOR AN AUTOMOBILE

Ralph R. Cook, Chicago, Ill.

Application August 29, 1934, Serial No. 53,105

Term of patent 3½ years

To all whom it may concern:

Be it known that I, Ralph R. Cook, a citizen of the United States of America, residing at 4225 Elston Avenue, Chicago, Illinois, have invented a new, original, and ornamental Design for an Automobile, of which the following is a specification, reference being had to the accompanying drawing, forming a part thereof.

Fig. 1 is a side elevational view; Fig. 2 is a front elevational view and Fig. 3 is a rear view, Figs. 2 and 3 being on a somewhat enlarged scale to that shown in Fig. 1.

I claim:

The ornamental design for an automobile substantially as shown.

RALPH R. COOK.
